UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 18,217, dated March 27, 1888.

Application filed February 23, 1888. Serial No. 265,055. Term of patent 3½ years.

To all whom it may concern:

Be it known that I, JENNIE SHEILS, of the city, county, and State of New York, have invented and produced a new and original Design for a Pattern of a Lady's Walking-Skirt; and I do hereby declare that the engraved prints accompanying this specification convey to any one accustomed to using paper patterns a clear understanding of how a garment made up by the pattern will appear.

The design shows a round walking-skirt that displays a full tablier reaching to the edge of the skirt at the left side of the front, falling in jabot folds at the right side of the front, in flaring folds from the belt, and in a short pan-

nier on the right hip, and a full back drapery falling to the edge of the skirt at the left side, and exhibiting jabot folds at the right side, bournous loopings at the top, and jabot folds below the loops.

What I claim as my invention, and desire to secure by Letters Patent, is—

The design for a lady's walking skirt, as shown in the engraved prints accompanying this specification.

JENNIE SHEILS.
